Primary Examiner — R. Johnson(74) *Attorney, Agent, or Firm* — Matthew J. Spark; Stefan J. Kirchanski; Zuber Lawler & Del Duca LLP(57) **CLAIM**

The ornamental design for a chair cushion, as shown and described.

DESCRIPTION

FIG. 1 is a top, left, front perspective view of a chair cushion showing my new design as used on a folding chair;

FIG. 2 is a top, left, rear perspective view thereof;

FIG. 3 is a front view thereof, shown unattached from the chair;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a top plan view thereof, the chair cushion shown laid flat; and,

FIG. 10 is a bottom plan view thereof.

The broken lines depict a folding chair and portions of the chair cushion, which form no part of the claimed design.

1 Claim, 7 Drawing Sheets(56)
